(57) **CLAIM**

The ornamental design for a moldable fabric kayak, as shown and described.

DESCRIPTION

FIG. 1 is a perspective view of the moldable fabric kayak ornamental design.

FIG. 2 is a top plan view of the moldable fabric kayak ornamental design.

FIG. 3 is a bottom plan view of the moldable fabric kayak ornamental design.

FIG. 4 is a right elevational view of the moldable fabric kayak ornamental design; the left elevational view being a mirror image thereof.

FIG. 5 is a front elevational view of the moldable fabric kayak ornamental design; and,

FIG. 6 is a rear elevational view of the moldable fabric kayak ornamental design.

FIG. 7 is a greatly enlarged partial view showing the configuration of the surface of the moldable fabric kayak.

The dash-dot broken lines defining the boundaries of the fabric covered areas represent the bounds of the claim and all other dashed broken lines show environmental structure which are for illustrative purposes only. None of the broken lines form a part of the claimed design. The fragmentary depiction of the fabric on the kayak is understood to cover the shaded surfaces of the moldable fabric kayak within the broken line boundaries of the claim.
